(57) **CLAIM**

The ornamental design for griddle, as shown and described.

DESCRIPTION

FIG. 1 is a perspective view of a griddle according to the present invention;

FIG. 2 is a first plan view of the griddle of FIG. 1;

FIG. 3 is a second plan view, opposite the first plan view, of the griddle of FIG. 1;

FIG. 4 is a first side view of the griddle of FIG. 1;

FIG. 5 is a second side view, opposite the first side view, of the griddle of FIG. 1;

FIG. 6 is a third side view, rotated ninety degrees from the first side view, of the griddle of FIG. 1; and,

FIG. 7 is a fourth side view, opposite the third side view, of the griddle of FIG. 1.
